United States Patent Office

Des. 197,317
Patented Jan. 7, 1964

197,317

AIR DIFFUSER

George J. Sweeney, Plandome, N.Y., and Rocco R. Borzone, Emerson, N.J. (both of 185 Madison Ave., New York, N.Y.)

Filed Mar. 15, 1963, Ser. No. 73,979

Term of patent 14 years

(Cl. D62—4)

FIG. 1

FIG. 2

FIG. 3

FIG. 4

FIG. 5

FIG. 1 is a bottom plan view of the air diffuser showing our new design;

FIG. 2 is a side elevational view;

FIG. 3 is a top plan view;

FIG. 4 is a side sectional view taken upon the line 4—4 of FIG. 1;

FIG. 5 is a horizontal upward sectional view taken upon the line 5—5 of FIG. 4 upon a reduced scale as compared to FIG. 4.

The dominant features of our design reside in the portions shown in full lines.

We claim:

The ornamental design for an air diffuser, as shown and described.
